UNITED STATES PATENT OFFICE

RALEIGH J. ADAMS, OF CHICAGO, ILLINOIS

BOILER CONSTRUCTION

Application filed June 18, 1926. Serial No. 116,856.

My invention relates to boiler construction and has among its other objects the production of an improved water tube boiler which is efficient and comprises elements which may 5 be assembled with a minimum of effort and expense.

A particular object of the invention is to provide an improved water tube boiler of the kind described wherein the several drums are 10 so arranged that they may be connected to each other by a relatively large number of water tubes which may be quickly and easily installed.

Many other objects and advantages of the 15 construction herein shown and described will be obvious to those skilled in the art from the disclosure herein given.

To this end my invention consists in the novel construction, arrangement and combination 20 of parts herein shown and described, and more particularly pointed out in the claims.

In the drawings, wherein like reference characters indicate like or corresponding 25 parts:

Fig. 1 is a vertical longitudinal section taken through a boiler embodying one form of the invention; and

Fig. 2 is a vertical longitudinal section 30 taken through a boiler embodying another form of the invention.

Referring for the present to Fig. 1, wherein I have shown a boiler embodying a preferred form of the invention, the reference 35 character 10 designates generally the setting of the boiler. In this instance, the setting 1 comprises side walls 11 and front and rear walls 12 and 13, respectively, the setting being provided with any suitable grate, as indicated at 15.

The improved boiler comprises a plurality of steam and water drums 17, 18, 19 and 20 of which the drum 18 is a mud drum and the drums 17 and 19 are front and rear steam 45 drums, respectively. As shown, the drums 17 and 19 are preferably disposed at the same elevation and communicate directly with each other through a bank of tubes 21. The intermediate drum 20 is preferably disposed 50 below and between the drums 17 and 19. The

mud drum 18 is the lowermost drum and is preferably disposed slightly in front of the drum 19 and slightly to the rear of the drum 20. The drums 17 and 18 communicate directly with each other through a bank of inclined water tubes 24 which are set at the greatest incline the head room will allow in order to get the maximum heating surface in this bank as this bank is subjected to the hottest gases. The drums 17 and 20 are connected directly to each other by a bank of tubes 26 which are preferably inclined so that they will drain into the drum 20. A bank of tubes 27 connect the drum with the mud drum 18 and the drum 19 is connected to the mud 65 drum by a bank of tubes 29. It will be noted that a relatively large number of tubes 29 are provided, this construction being permitted by the position of the drum 20. Reference is made to my copending application, Serial No. 568,114, filed June 14, 1922, patented July 20, 1926, Patent No. 1,592,818, wherein I have shown a boiler of similar construction, wherein the three rear drums are disposed in substantially vertical alignment 70 so that it is relatively difficult to provide a large number of tubes connecting the uppermost drum with the mud drum. 75

The hot gases may be directed through the several banks of tubes in any desired manner, but in this embodiment of the invention baffles 30, 31 and 32 are provided. As shown, the baffle 30 is disposed in front of the bank of tubes 27 and extends from the drum 20 to the mud drum 18. The baffle 31 is disposed in front of the bank of tubes 29 and extends from the drum 19 to a point intermediate the drums 19 and 18. The baffle 32 extends forward and downward from the baffle 31 and its free end is disposed in close proximity to the bank of tubes 30. It is readily understood that the hot gases will pass upward through the banks of tubes 24 and 26 and then downward through the bank of tubes 27, after which the hot gases will flow 80 upward through the bank of tubes 29 and be discharged from the boiler through the flue 33. It will be noted that baffle 32 insures that all of the hot gases will come in contact with the tubes 27. In practice, the drums and 85 90 95 100

tubes of the boiler shown in Fig. 1 may be assembled in less time and with less effort than the tubes and drums of the boiler shown in the copending application.

5 Water is preferably admitted to the boiler through a pipe 36 which projects into the drum 19 and steam escapes from the boiler through a fitting 37 which communicates with a dry pipe 38 of well known construction disposed within the drum 19.

10 The operation of the above described boiler is substantially as follows: Water is admitted to the drum 19 and travels through the tubes 29 and to the mud drum 18, and then circulates through the tubes 24, the drum 17, the tubes 26, the drum 20, the tubes 27 and the mud drum, a portion of the water passing as steam through the tubes 21 to the drum 19 and thence through the fitting 37.

15 In Fig. 2 I have shown another preferred form of the invention embodied in a boiler which comprises a setting 40 which is preferably of the same form as the aforementioned setting 10. The drums 17, 18, 19 and 20 are duplicated in the setting 40 and are identified by the reference characters 41, 42, 43 and 44, respectively. The aforementioned banks of tubes 21, 24, 26, 27 and 29 are also duplicated in the setting 40 and are identified by the reference characters 46, 47, 48, 49 and 50, respectively. Feed water is admitted to the rear steam drum 43 by a pipe 52 and steam escapes from the boiler through a fitting 53 provided upon the drum 43, a dry pipe 54 of well known construction being disposed within the drum 43 to deliver steam to the fitting 53.

20 The boiler shown in Fig. 2 also embodies a preferred form of the invention, but, in this instance, I provide a plurality of baffles which are disposed differently than those disposed in Fig. 1. Thus, in the boiler shown in Fig. 2, I have provided baffles 57, 58, 59, 60, 61, 62, 63 and 64. The baffle 57 extends between the drum 44 and the front steam drum 41, the baffle being disposed immediately above the tubes 48. The baffle 58 extends between the drums 43 and 44 and the baffle 59 extends from the mud drum 42 to a point intermediate the drums 42 and 41. As shown, the baffle 59 is disposed in close proximity to the uppermost row of tubes 47 and has the laterally extending baffle 60 associated with it, the baffle 60 being adapted to guide the hot gases into the bank of tubes 49. The baffle 61 extends from the drum 44 to a point intermediate the drums 44 and 42, the baffle 61 being disposed in close proximity to the rear row of tubes 49. The baffle 62 extends rearwardly from the baffle 61 and is adapted to guide the hot gases into the bank of tubes 50. The baffles 63 and 64 extend from the rear wall of the setting 40 to the rear row of tubes 50.

25 65 It is readily understood that when the

boiler is in operation the hot gases will pass upwardly through the bank of tubes 47 into the bank of tubes 48 and thence downwardly through the bank of tubes 49 into the bank of tubes 50, whereupon the hot gases will flow upward along the tubes 50 and be discharged from the setting. I have indicated a flue 66 in the top wall of the setting 40 and a traveling grate 68 in the combustion chamber 69 formed in the setting 40. However, it is to be understood that I am limited to this construction only to the extent indicated in the appended claims.

30 Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

35 What I claim as new and desire to secure by Letters Patent is:

1. In a device of the class described, a boiler including an enclosure having a combustion chamber at the bottom thereof, and a flue at the top thereof, a combined water inlet and steam outlet drum adjacent the flue, a second drum on a level with the said combined drum, a bank of tubes for feeding steam only from the second drum to the combined drum, a mud drum rearwardly of the combustion chamber, a bank of tubes connecting the combined drum and the mud drum for conducting incoming water directly to the mud drum, a relatively long bank of tubes connecting the mud drum with the second drum and being located above the combustion chamber to have contact throughout their lengths with the hot gases rising directly from the combustion chamber, a fourth drum located on a plane below the combined drum and the second drum and out of vertical alinement with both to permit hot gases to pass entirely around said fourth drum, a bank of tubes connecting the mud drum with the fourth drum, a relatively short forwardly inclined bank of tubes connecting the fourth drum with the second drum and arranged in the path of travel of the hot gases directly after they have passed through the said relatively long bank of tubes, and baffles for causing the gases to travel downwardly along the bank of tubes connecting the mud drum and the fourth drum and upwardly along the bank of tubes connecting the mud drum and the combined drum.

2. In a device of the class described, a boiler including an enclosure having a combustion chamber at the bottom thereof, and a flue at the top thereof, a combined water inlet and steam outlet drum adjacent the flue, a second drum on a level with the said combined drum, a bank of tubes for feeding steam only from the second drum to the combined

drum, a mud drum rearwardly of the combustion chamber, a bank of tubes connecting the combined drum and the mud drum for conducting incoming water directly to the mud drum, a relatively long bank of tubes connecting the mud drum with the second drum and being located above the combustion chamber to have contact throughout their lengths with the hot gases rising directly from the combustion chamber, a fourth drum located on a plane below the combined drum and the second drum and out of vertical alinement with both to permit hot gases to pass entirely around said fourth drum, a bank of tubes connecting the mud drum with the fourth drum, a relatively short forwardly inclined bank of tubes connecting the fourth drum with the second drum and arranged in the path of travel of the hot gases directly after they have passed through the said relatively long bank of tubes, a baffle extending longitudinally of, and close to the bank of tubes connecting the mud drum with the fourth drum for permitting hot gases to travel vertically through the relatively long bank of tubes without contacting with the tubes connecting the mud drum and the fourth drum, and an additional baffle extending lengthwise of the last mentioned bank of tubes and the bank of tubes connecting the combined drum and the mud drum for causing the gases to travel first through the bank of tubes connecting the mud drum and the fourth drum and then through the bank of tubes connecting the mud drum and the combined drum.

In testimony whereof, I have hereunto signed my name.

RALEIGH J. ADAMS.
